United States Patent Office

Des. 228,618

Patented Oct. 16, 1973

228,618

LOCK

Sidney Falk, Chicago, Ill., assignor to Fort Lock Corporation, Chicago, Ill.

Filed Feb. 11, 1972, Ser. No. 225,693

Term of patent 14 years

Int. Cl. D8—07

U.S. Cl. D8—113

FIG. 1 is a perspective view of the lock showing my new design.

FIG. 2 is a fragmentary plan view showing the lock body and associated structural detail.

FIG. 3 is an end view showing the end of the lock body.

FIG. 4 is a plan view taken substantially in the plane of the line 4—4 in FIG. 2 and showing the top of the lock body.

I claim:

The ornamental design for a lock, as shown.
